UNITED STATES PATENT OFFICE.

ARTHUR PENTECOST, OF EAST ORANGE, NEW JERSEY, ASSIGNOR TO PIKE ADDING MACHINE COMPANY, OF ORANGE, NEW JERSEY, A CORPORATION OF NEW JERSEY.

ATTACHMENT FOR PLATEN-CARRIAGES.

No. 918,587.

Specification of Letters Patent. Patented April 20, 1909.

Application filed May 24, 1906. Serial No. 318,545.

To all whom it may concern:

Be it known that I, ARTHUR PENTECOST, a subject of the King of Great Britain, and residing at East Orange, in the county of 5 Essex and State of New Jersey, have invented certain new and useful Improvements in Attachments for Platen-Carriages, of which the following is a specification.

My invention relates to attachments for 10 platen carriages such, for instance, as are used upon different classes of adding and other machines where it is desirable to move a platen to, and arrest it in one or more different predetermined positions in order 15 to make any desired records thereon, and my invention consists in means for accurately arresting the carriage as required and for securing it in place upon its frame or support, and for releasing the same when required, as fully set forth hereinafter, and 20 as illustrated in the accompanying drawing, in which:

Figure 1 is a sectional view illustrating 25 part of the frame of an adding machine with a sliding carriage and with my improved attachment; and Fig. 2 is a rear elevation of the parts.

The carriage B is provided with the usual, or any suitable platen C, and slides 30 upon a support or frame A, being guided in any suitable manner.

In order to temporarily arrest the sliding movement of the carriage I make use of a stop bar D which is provided with a suitable 35 stop, or, if desired, with a plurality of stops E, secured adjustably to said bar so as to be set by hand in any desired position or positions, and on the carriage is a finger F yieldingly connected with the carriage and 40 normally pressed toward the bar, and which by its contact with a stop will hold the carriage in its desired position. As shown, each stop has two reversely inclined edges α , α , and an intermediate notch γ , and as the carriage 45 is moved in one direction or the other the finger, if in contact with either raised edge, will depress the bar D until said finger alines with the intermediate notch, when it will enter the latter and hold the carriage in place, the bar D being of course 50 moved upward by springs, hereinafter referred to, as soon as the finger passes from the inclined part α . Suitable means are combined with the finger for pressing it

toward the bar, and for raising it. As 55 shown, the finger is carried by a shaft 3 to which is connected a bell crank lever or arm H, and to one arm 5 of the lever is connected a spring 6 which tends to rock the shaft to carry the finger toward the edge 60 of the bar, and by applying the forefinger to the lever H and the thumb to a horn 7 on the carriage the shaft may be readily rocked against the stress of the spring, lifting the finger away from the edge of the bar 65 sufficiently to permit the carriage to be moved back and forth. When it is necessary to lift the finger out of the notch of the stop, the lever H will of course be moved to correspondingly elevate the finger. It is desirable however that when the carriage is in 70 a position, with the finger depressed and out of contact with a stop, or above the stop but out of line with the notch thereof, that the carriage may be held or clamped to the 75 support so as not to move too readily, and I therefore provide frictional clamping means 80 preferably connected so as to be released whenever the finger is lifted, and so as to be applied when the finger is depressed sufficiently to contact with the upper edge 85 of the bar. To this end the bar D is yieldingly connected to the frame or support. As shown, it has arms 9, 9, extending at right angles and pivoted to the support by 90 pivots 10 with springs 12 tending to lift the bar, but are not of a strength to overcome that of the spring 6.

The shaft 3 carries an eccentric 13 which is the hub of the finger F, and when the shaft is turned by the spring 6 to carry the finger downward against the bar D, the eccentric will bind or bite against the support and clamp the carriage in place, the bar yielding to an extent to permit the finger to move downward sufficiently for the eccentric to thus bite against the support. It will thus be seen that the eccentric is operative to prevent free longitudinal movement of the carriage, when the finger F is not engaged in the notch γ of the stop, which acts to positively lock the carriage from longitudinal movement on the support; and when the shaft 3 is rocked by the arm H said eccentric is carried out of clamping position. 95 100 105

It will be evident that there may be a single stop, but that by a plurality of stops I am enabled to set the carriage in different

5 predetermined positions desired, and while different means of adjusting the stop or stops may be employed, I prefer to provide the bar with a slot *w* into which extends a 10 guide lug 15 from each stop and through which passes the shaft of a clamp screw 16 into the stop, and by turning the said screw in one direction or the other the stop may be released, set in position, and then secured.

10 Further it will be evident that said series of stops may be used with different contact devices.

Without limiting myself to the construction shown, I claim:

15 1. The combination with a platen carriage and with a support therefor, of a bar parallel to the platen and attached to said support, a stop secured adjustably on the bar, a stop finger extending at right angles 20 to the bar from the carriage in position to normally contact with said stop, and means for shifting said finger to carry it out of position to contact with the stop.

25 2. The combination with a platen carriage and with a support therefor, of a bar parallel to the platen and attached to said support, a plurality of stops secured adjustably 30 on the bar, a stop finger extending from the carriage at right angles to the bar in position to normally contact with said stops, and means for shifting said finger to carry it out of position to contact with the stop.

35 3. The combination with a platen carriage and with a support therefor, of a bar attached to said support, a stop secured adjustably on the bar and provided with a notch, a stop finger extending from the carriage in position to normally contact with said stop, means for shifting said finger to 40 avoid such contact, and a clamp connected to hold the carriage on the support when said finger is in normal position.

45 4. The combination with the sliding platen carriage and support therefor, of a bar provided with an adjustable notched stop, a finger carried by the carriage and movable to engage and disengage said stop, and means connected with the finger for clamping the carriage to the support.

50 5. The combination with the platen carriage and support on which the carriage slides, of a stop bar, a movable stop thereon provided with a notch, and a shaft on the carriage provided with a finger for contacting with the stop of said bar.

55 6. The combination with the platen carriage and support on which the carriage slides, of a stop bar provided with a series of adjustable stops, a shaft on the carriage provided with a finger for contacting with the stops of said bar, and an eccentric carried by the shaft to engage the support when the finger is engaging the stop bar.

60 7. The combination with the platen carriage and support on which the carriage

slides, of a stop bar provided with a plurality of notched stops, a shaft on the carriage provided with a finger for contacting with the stop of said bar, an eccentric carried by the shaft to engage the support 70 when the finger engages the stop bar, and means for rocking the shaft.

75 8. The combination with a platen carriage and a support on which it slides, of a clamp carried by the carriage and normally engaging the support to prevent free movement of the carriage on said support, a finger carried by the carriage, a stop on the support adapted to be engaged by said finger to positively lock the carriage against longitudinal movement, and means for releasing said clamp and disengaging said finger from said stop.

80 9. The combination with a platen carriage and a support on which it slides, of a finger carried by the carriage, a plurality of stops on the support each adapted to engage said finger and positively lock the carriage in position on the support, clamping means for preventing free movement of the carriage 85 on the support when said finger is disengaged from said stops, and means for releasing said clamping means.

90 10. The combination with a platen carriage and a support on which it slides, of a shaft mounted on the carriage, a finger carried by said shaft and adapted to engage a stop on said support to positively prevent movement of the carriage on the support, independent clamping means connected with 95 said shaft and constantly tending to engage the support to prevent free longitudinal movement of the carriage, and means for rocking said shaft to disengage the finger from said stop and release said clamping 100 means.

105 11. The combination with a platen carriage and a support on which it slides, of a shaft mounted on the carriage and having a finger adapted to engage a stop to positively prevent longitudinal movement of the carriage on its support, an eccentric on said shaft adapted to engage the support, a spring acting to hold said shaft in position to cause the eccentric thereon to engage the support and said finger to engage said stop, and means for rocking the shaft in opposition to said spring.

110 12. The combination with a platen carriage and a support on which it slides, of a stop finger connected with said carriage, a plurality of stops arranged to make contact with said finger, and means for changing the relative positions of stops and finger to insure or avoid contact as desired.

115 13. The combination with a platen carriage and a support on which it slides, of a stop finger yieldingly connected with said carriage, a bar over which the finger extends, and a plurality of stops adjustably 120

connected with said bar and having reversely inclined edges and an intermediate notch.

14. The combination with a platen carriage and a support on which it slides, of a stop finger yieldingly connected with said carriage, a bar over which the finger extends, a stop adjustably connected with said bar and having reversely inclined edges and 10 an intermediate notch, and means for shifting said finger.

15. The combination with a platen carriage and a support on which it slides, of a stop finger yieldingly connected with said carriage, a bar over which the finger extends, a stop adjustably connected with said bar and having reversely inclined edges and 15

an intermediate notch, and a hand lever for shifting said finger.

16. The combination with a platen carriage and a support on which it slides, of a stop bar having a yielding connection with said support, a finger yieldingly connected with said carriage and bearing on said bar, a clamp on the carriage, and means for 20 25 shifting the finger and clamp simultaneously out of operative position.

In testimony whereof I affix my signature in presence of two witnesses.

ARTHUR PENTECOST.
